(57) **CLAIM**

The ornamental design for a sheave with domed gussets, as shown and described.

DESCRIPTION

FIG. 1 is a perspective view of a sheave with domed gussets showing my new design;

FIG. 2 is a front view thereof;

FIG. 3 is a left side view thereof;

FIG. 4 is a top view thereof; and,

FIG. 5 is a sectional view taken along section lines 5—5 of FIG. 4.

The rear view is a mirror image of the front view shown in FIG. 2.

The right side view is a mirror image of the left side view shown in FIG. 3.

The bottom view is a mirror image of the top view shown in FIG. 4.

The broken lines in the drawing represent unclaimed environmental material.
